[57] CLAIM

The ornamental design for a extendable tub brush, as shown and described.

DESCRIPTION

FIG. 1 is a side elevational view of an extendable tub brush embodying our new design, with the handle shown broken away to indicate indeterminate length;

FIG. 2 is a top plan view with the handle and top bristles omitted, shown separately for ease of illustration;

FIG. 3 is a bottom plan view with the handle and bottom bristles omitted, shown separately for ease of illustration;

FIG. 4 is an end elevational view as seen from the left of FIG. 2;

FIG. 5 is an end elevational view as seen from the right of FIG. 2;

FIG. 6 is a cross sectional view taken on line 6—6 of FIG. 1, with the handle omitted; and,

FIG. 7 is a cross sectional view taken on line 7—7 of FIG. 1, with the handle omitted.
